CLAIM

The ornamental design for a pig shoe, as shown and described.

DESCRIPTION

FIG. 1 is a front, left and bottom perspective view of a pig shoe, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

A right shoe of the pig shoe is a mirror image of the left shoe as shown in FIGS. 1 to 7.
